UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,307,688.

Specification of Letters Patent. Patented June 24, 1919.

Application filed December 2, 1916. Serial No. 134,571.

To all whom it may concern:

Be it known that I, FRANK A. LUNDQUIST, a citizen of the United States, residing at New York, in the county of New York and State of New York, have invented certain new and useful Improvements in Telephone Systems, of which the following is a full, clear, concise, and exact description.

This invention relates to telephone systems, and more particularly to automatic switches employed in such systems.

The object of this invention is the provision of a new and improved automatic switch of increased capacity which may be directly controlled by series of impulses.

The main feature of this invention is the provision of a selective switch having a plurality of sets of terminals and a plurality of sets of brushes arranged to be directly moved into engagement with certain sets of terminals under the control of an impulse transmitter, and means operated under the control of the impulse transmitter irrespective of the number of impulses transmitted for selecting the set of brushes to be used.

Although the principles of the invention are herein shown applied to a connector switch, they may with the usual modification, be applied to a selector switch.

The invention is illustrated in the accompanying drawing in which Figure 1 shows a side elevation of a connector switch, and a circuit arrangement by which the switch may be controlled and Fig. 2 shows a perspective view of the operating parts of a sender for controlling the operation of the switch.

The switch herein disclosed is arranged to have ten vertical or group selecting positions and ten rotary or line selecting positions.

A and B designate two banks of contacts or terminals of 100 lines each, with which two sets of brushes "a" and "b" coöperate. The brushes "a" normally rest two steps below the first group of terminals in the bank A, while it is necessary to raise the switch one step to bring the brushes b opposite the first group of terminals in the bank B.

The brush set "a" is mounted above the brush set "b" on a brush shaft 6, which shaft is supported for vertical and rotary movement in a frame (not shown). A rotary ratchet 7 and a vertical ratchet 8 are provided on the brush shaft with which

pawls carried by the armatures of the rotary magnet RM and the vertical magnet VM respectively engage to operate shaft 6. A collar 10 provided with a rod 9 is rotatably mounted near the bottom of the shaft 6 but is held against vertical movement on the shaft in any suitable manner. This rod 9, near its lower portion carries a heel 11 which functions in a manner to be described. A bell-crank lever 13 pivoted to the frame 65 has at the end of one of its arms, a rounded portion 12 which engages the heel 11 when the shaft 6 has been moved up one step. The engagement of the rounded portion 12 and heel 11 causes the elevation of the arm 70 14 of said lever. A rod 15 pivoted to the upper end of the armature of a magnet 5 normally rests on the arm 14 of the bell-crank lever 13.

A side switch 31 provided with a contact 75 arm and contacts of usual structure and arrangement is actuated by a spring 32 to move in a counter-clockwise direction under the control of an escapement 17. A rod 16 pivoted to the upper end of this escapement 80 member 17, will be engaged by the rod 15 upon the energization of magnet 5 at all times after the second vertical step of the shaft 6. The side switch 31 will be advanced one position each time that the rod 16 is 85 returned to its normal position by the action of the spring 33 after it has been actuated to the right by the rod 15.

A dash pot 20 mounted on the frame is provided with a plunger arm 19. This 90 plunger arm 19 carries lugs 18 and 22 and insulated arms 25 and 26, and terminates at its left end in a transverse roller 21. When the shaft 6 has been raised one step and the magnet 5 is energized, the rod 15 which now 95 presses against the rod 18 will move the plunger arm 19 to the right. If the shaft 6 is now raised a second step, the rod 9 will engage the roller 21 to hold the plunger arm in its off-normal position against the action 100 of spring 24, until the switch is restored to normal. If, however, the magnet 5 is not energized after the shaft 6 has taken its first vertical step, the rod 9 after the second vertical step will engage the roller 21 in such 105 a way as to hold the plunger arm 19 in normal position until the switch is restored. The rod 9 is held by guides (not shown) so as to travel vertically with the shaft 6 but not to rotate with said shaft.

A rod 23 pivoted to the frame is controlled by the lug 22 so as to break the circuit from magnet 5 to contact springs 40 when arm 19 is in any position but normal. 5 The arms 25 and 26 on the arm 19 engage the contact springs 27 and 28 when said arm is in normal position, and engage contact springs 29 and 30 when the arm 19 is moved to the right.

10 The vertical and rotary ratchets 7 and 8 are held by pawls 36 and 37, respectively, which are pivoted on the frame. These pawls are spring-actuated and engage the ratchets whenever plunger arm 35 of a dash 15 pot 34 is held in off-normal position. This dash pot 34 is mounted on the frame and its arm 35 is normally held in engagement with the above mentioned pawls by spring 39. This arm 35 is moved to the left by the 20 energization of relay 4 whose armature engages a lug on the arm. When in normal position, the plunger arm holds pawl 36 out of engagement with its ratchet and a lug 38 carried on the plunger arm holds pawl 37 25 inoperative. The dash pot 34 is adjusted so as to release its arm 35 very slowly.

A bell crank lever 46, pivotally mounted on the frame, engages with one arm the bottom of the shaft 6 and with the other arm 30 the contact arm of the side switch 31. When the shaft 6 is returned to normal the lever 46 operates to restore the side switch.

Contact springs 40 are normally open and will be closed only when the projection 11 35 forces rounded portion 12 against them. Contact springs 41 will close when the brush shaft 6 has taken two vertical steps and will remain closed thereafter until the switch is restored.

40 An impulse sender generally designated as 47 is provided with two sets of contact springs 1 and 2 which will be included in the controlling circuit of the switch to be operated. This sender is provided with dials 45 48 and 49 with each of which characters are associated. The characters associated with the dial 48 may be numerals such as 1 to 0, and those associated with the dial 49 may be letters. The dial 48 operates independently of dial 49 to open and close the springs 50 1. The dial 49 is arranged to carry the dial 48 with it by means of pin 60 when operated and thereby to operate the springs 1 as though the dial 48 had been used. In addition to operating the springs 1, and before such operation occurs, the finger of the operator when using the dial 49 will engage a movable finger lever at a sufficient period of time before engaging the stationary finger 55 60 stop in order to cause a single opening of the springs 2 for a period considerably longer than that of an impulse through the springs 1.

Current is normally supplied to the calling subscriber's substation from battery

through the windings of the retardation coil 42, but when the line is in use the battery will be removed by the opening of off-normal contact ON of the line switch indicated diagrammatically at LS and will be replaced 70 by battery at relay 3.

Further details will be understood from the following description of the operation of the switch.

When the subscriber removes his receiver 75 from the hook a line switch LS will pick out an idle connector circuit, whereupon relay 3 will be energized from battery, through its winding, lower wiper of LS, switchhook SH, contact springs 1 and 2, left-hand winding of 42, to ground. If the subscriber desires connection with a line whose terminals are in the bank A he will operate his sender using the numeral corresponding to the first digit of the number of the called line, and 80 will thus cause a series of impulses to be sent out by the intermittent breaking of the previously described energizing circuit of the relay 3, at the contact spring 1. When the relay 3 was first energized it closed a circuit for energizing the slow release relay 4 from battery, armature and front contact of relay 3, winding of relay 4, to ground. 90

The energization of the relay 4 caused the holding pawls to engage the vertical and 95 rotary ratchets. When the subscriber dials, the armature of the relay 3 vibrates, and each time the relay 3 is deenergized a circuit is closed from battery, armature and back contact of relay 3, armature and front 100 contact of relay 4, contact arm of side switch 31 (position 1), through the winding of the vertical magnet VM, to ground. This results in the elevation of the brush shaft 6 until brushes "a" are opposite the group of 105 terminals in which the desired line terminates.

When the numerals on the dial are used, the first two impulses sent through the springs 1 raise the brushes "a" to the first 110 group of line terminals. After the second impulse the springs 41 will be closed and the slow release magnet 5 will be energized from battery, armature and back contact of the relay 3, springs 41, through the winding 115 of the magnet 5, to ground, and will be held up through the remainder of the series of impulses. When magnet 5 is energized rod 15 will push the rod 16 to the right so that the side switch will step into its second position upon the release of the magnet 5, which occurs at the end of the first series of impulses. 120

The subscriber now dials again, sending out a second series of impulses over the circuit previously traced as far as the side switch which is now in position 2, so that impulses are transmitted thence over the wire 45 to the rotary magnet RM. During this series of impulses the slow magnet 5 125 130

will again be energized and at the end of the impulses will move the side switch 31 into its third, or idle position. Brushes "a" will now rest on the terminals of the desired line and will be connected to the calling substation through springs 27 and 28, insulated arms 25 and 26, wires 43 and 44, and the wipers of the line switch LS.

If, however, a subscriber desires connection with a line having terminals in the bank B, he dials with the letters instead of the numerals for the first series of impulses. The contact springs 2 will be opened, causing the retraction of the armature of the relay 3, which sends one impulse from battery, armature and back contact of relay 3, armature and front contact of relay 4, side switch 31 (position 1) through the winding of the vertical magnet, to ground, to elevate shaft 6 one step. Immediately after the sending of this impulse the armature of the relay 4 will drop back, and an energizing circuit for magnet 5 will be closed from battery, armature and back contact of the relay 3, armature and back contact of the relay 4, contact springs 40, which are now closed since the shaft 6 has been elevated one step, rod 23, through the winding of the magnet 5 to ground.

The attraction of the armature of magnet 5 causes the rod 15 to engage lug 18, which it rests against, after the first vertical step of the brush shaft, thus causing the movement of the plunger arm 19 to the right. Contact springs 2 will now close, causing the energization of relay 3 and relay 4. The armature of relay 4 was not retracted for a sufficiently long time to allow plunger 35 to return to normal, which would have removed holding pawl 36 from the vertical ratchet and allowed the brush shaft 6 to drop back to normal. When the closure of the contact springs 2 resulted in the energization of the slow relay 4, the circuit for holding up magnet 5 was broken at the back contact of relay 4, and magnet 5 became de-energized. The plunger arm 19, however, being held by the dash pot 20 did not have time to return to normal before the second step of the brush shaft caused the rod 9 to engage roller 21 and hold arm 19 in its right-hand position.

Immediately after the closure of the contact springs 2 a series of impulses is sent out, which causes the armature of the relay 3 to vibrate, transmitting impulses over the circuit previously traced to the vertical magnet so that the brush shaft is lifted until the brushes "b" are opposite the group of terminals containing the desired line. At the conclusion of this series of impulses magnet 5 again becomes de-energized, allowing the side switch to step into its second position.

The subscriber now dials again with the result that the rotary magnet is intermit-

tently energized until the brushes "b" rest on the terminals of the desired line, at which time the subscriber will be connected through line switch LS, wires 43 and 44, insulated arms 25 and 26, now in their right-hand position, springs 29 and 30, to the brushes "b."

At the end of the conversation, when the subscriber hangs up his receiver, he breaks at his switchhook SH the holding circuit of relay 3, which retracts its armature. The consequent de-energization of the relay 4 is followed by the return of the plunger arm 35 to normal, which disengages the holding pawls 36 and 37 from their respective ratchets and allows the brush shaft 6 to be rotated back to normal by the usual spring (not shown), and to fall into a normal position under the influence of gravity. When it reaches bottom, the end of shaft 6, pressing on one arm of the bell crank lever 46, will cause the restoration of the side switch 31, and the apparatus is ready for the next call.

What is claimed is:

1. In a telephone system, telephone lines, selective switches arranged to interconnect said lines, said switches being provided with a plurality of banks of fixed terminals and a set of brushes to travel over and make contact simultaneously with the terminals of each of said banks respectively, an impulse transmitter, means for connecting said impulse transmitter to any one of said switches, and means at each switch controlled by the first impulse transmitted thereto from said impulse transmitter for determining the particular set of brushes at said switch to be used.

2. In a telephone system, telephone lines, selective switches arranged to interconnect said lines, said switches being provided with a plurality of banks of fixed terminals and a set of brushes to travel over and make contact with the terminals of each of said banks respectively, an impulse transmitter, means for connecting said impulse transmitter to any one of said switches, and means at each switch controlled by the character of the first impulse transmitted thereto from said impulse transmitter for determining which of said sets of brushes at said switch shall be used.

3. In a telephone system, an incoming line, a plurality of outgoing lines, an automatic switch arranged to select any one of said outgoing lines, means for connecting said incoming line to said switch, said switch being provided with a plurality of sets of brushes arranged to engage simultaneously contacts of said switch, an impulse transmitter associated with said incoming line and arranged to directly control said switch, and means directly controlled by first impulse transmitted from said impulse transmitter when associated with said switch

- for determining which of said sets of brushes shall be used.
4. In a telephone system, telephone lines, selective switches arranged to interconnect said lines, an impulse transmitter, said switches being provided with a plurality of banks of fixed terminals and a set of brushes to travel over and make contact with each of said banks of terminals, respectively, said impulse transmitter being arranged to operate from a plurality of sets of positions to send the same train of impulses from corresponding positions in each set of positions, a circuit changing device included in said impulse transmitter arranged to be differently actuated in each of said sets of positions, and means controlled by said circuit changing device for causing one or another of said sets of brushes to be used.
5. In a telephone system, telephone lines, selective switches arranged to interconnect said lines, an impulse transmitter, said switches being provided with two banks of fixed terminals and two sets of brushes arranged to travel over and make contact with the terminals of each of said banks, respectively, said impulse transmitter being arranged to be actuated from two sets of positions to send the same train of impulses from corresponding positions in each set of positions, a circuit changing device included in said impulse transmitter arranged to be actuated in one of said sets of positions only, and means controlled by said circuit changing device for causing one or the other of said sets of brushes to be used.

In witness whereof, I hereunto subscribe my name this 29th day of November, A. D. 1916.

FRANK A. LUNDQUIST.
